By J. F. Rule,
Their attorney.

UNITED STATES PATENT OFFICE.

DAVID DENELSBECK AND CLARENCE D. DILLE, OF NEWARK, OHIO, ASSIGNEES TO THE OWENS BOTTLE COMPANY, OF TOLEDO, OHIO, A CORPORATION OF OHIO.

WARE RACK.

Application filed April 2, 1924. Serial No. 703,687.

Our invention relates to apparatus for receiving and transporting from one place to another, various materials, articles of manufacture, merchandise, etc.

3 An object of the invention is to provide a simple and practical apparatus adapted for handling such articles or materials, with a minimum amount of labor and effort, particularly where such articles are received at one 10 level and are to be stored or placed at a higher or lower level.

Other objects of the invention and the precise nature thereof will appear more fully hereinafter.

15 In the accompanying drawings:

Figure 1 is a part sectional side elevation of an apparatus constructed in accordance with our invention.

20 Figure 2 is a part sectional end elevation of the same.

Figure 3 is a detail view showing a latch for holding a tray in elevated position.

Figure 4 is a sectional detail showing the hinge connections for the trays.

25 As herein shown, ware racks are mounted on a truck 10, adjacent its two ends. The truck may be a trailer of usual construction. Each rack frame is supported on a base 11, which may be bolted to the truck, said base

30 having an integral vertical stem or shaft 12. The rack-supporting frame is triangular in shape and comprises horizontal base strips 13 and inclined side strips 14. The frame is mounted for rotation on the shaft 12 by 35 means of bearing members 15 and 16. A frame piece 9 extending lengthwise of the frame forms a connection between the bearing member 16 and the strips 14. Strips 8 at the base of the frame form a connection 40 between the lower bearing member 15 and the strips 13.

45 Mounted in the upper end of the frame members 14 is a horizontal shaft 17 extending lengthwise of said frame. A pair of receptacles or trays 18 are supported on the inclined sides 14 of the triangular frame and may have a pivotal connection with the shaft 17 by means of hinge straps 19 secured to the bottoms of the trays and pivoted to the shaft

50 17. This construction permits either tray 18 to be swung from its downward position, upward to a position in line with the other tray, as indicated at the left hand side of

Figure 1. The upper tray is held in its elevated position by a latch 21 having a hinge connection 22 with the bottom of the tray. The frame carrying the trays can be rotated about the vertical axis of the shaft 12 and is normally held against rotation by a sleeve 23 having a detent 24 to engage a notch 27 in the bearing member 15. A plurality of notches 27 are preferably provided at intervals around the sleeve to hold the frame at any desired position. The sleeve 23 is yieldingly held down by a spring 25 and is prevented from rotating with the shaft, by a spline 26.

55 As a practical example of the utility of the present invention, its use for handling bottles or other glassware as delivered from the annealing leir may be referred to. For this purpose, the trailer 10 is moved to a convenient position at the delivery end of the leir and the bottles 29 or other articles are placed on the trays 18 while the latter are in their lowered position. After all the trays are loaded, the trailer may be moved to position for unloading. When the ware is to be stacked up or placed in a position higher than can be conveniently reached by a person unloading from a tray in its lowered position, the tray is swung upward to the elevated position shown at the left of Figure 1. The attendant can then, by standing on a platform, or at a suitable elevated position, readily 70 transfer the ware from the elevated rack to the desired position. When the upper tray has been emptied, it may be lowered and the other tray on the same frame elevated to position for unloading. The swivel connection permits both trays to be brought to the same elevated position without shifting the truck. It will be noted that the bottles are supported in an upwardly inclined position convenient 75 for handling, both when the tray is in its lowered position and also when swung up to its elevation position. The present invention obviates the need of tier machines which, prior to this invention, have ordinarily been used for elevating the truck, and also greatly 80 reduces the amount of handling of the ware, heretofore found necessary.

95 The use of the present invention in the handling and storing of glassware has been described merely as an example of the various 100 uses to which the invention may be applied.

Modifications of the apparatus and its manner of use, may be resorted to within the spirit and scope of our invention.

What we claim is:

- 5 1. The combination of a base comprising a pair of horizontally spaced interconnected triangular frames, each having downwardly and outwardly divergent sides, a horizontal pivot rod interconnecting the upper ends of
- 10 said frames, trays hinged to the rod and normally resting on said sides, said trays being free to be individually swung upwardly above the pivot rod into alignment with the other tray, and means to hold either
- 15 tray in the upward position.
2. The combination of a triangular frame having its sides downwardly and outwardly divergent, a horizontal pivot rod at the apex of said frame, trays hinged to said rod and respectively supported on the inclined sides of the frame, said pivot rod extending along the upper edges of the floors of the trays, each said tray comprising article supporting plates extending upwardly and outwardly from the floor of the tray at the ends thereof, each tray being free to be swung upward to a position substantially above and in line with the other tray while the latter is in its lowered position, means to hold the upwardly swung tray in its upward position, the adjacent said ends of the tray being arranged to abut when the trays are aligned and thereby limit the upward swinging movement of the upper tray.
- 35 3. The combination of a triangular frame having its sides downwardly and outwardly divergent, a horizontal pivot rod at the apex of said frame, trays hinged to said rod and respectively supported on the inclined sides of the frame, said pivot rod extending along the upper edges of the floors of the trays, each said tray comprising article supporting

plates extending upwardly and outwardly from the floor of the tray at the ends thereof, each tray being free to be swung upward to a position substantially above and in line with the other tray while the latter is in its lowered position, means to hold the upwardly swung tray in its upward position, the adjacent said ends of the tray being arranged to abut when the trays are aligned and thereby limit the upward swinging movement of the upper tray, a standard on which the frame is mounted for rotation about a vertical axis, and a spring detent to hold the frame in a predetermined rotative position.

4. The combination of a truck, vertical standards mounted thereon, triangular frames swivelly mounted on the standards, each said frame comprising a horizontal base and upwardly convergent sides, a horizontally disposed hinge rod at the apex of each frame, trays hinged to each said rod and extending downwardly along the sides of the frame, each tray being arranged to be swung upward about its hinge rod to a position in line with the other tray on the frame, each tray having at each end an article supporting end piece projecting upwardly and outwardly from the floor of the tray whereby each tray is provided with an end plate in article supporting position when the tray is in either its upwardly or downwardly swung position, the adjacent end plates of each pair of trays being arranged to abut when the two trays are in line and thereby limit the upward swinging movement of the upper tray.

Signed at Newark, in the county of Licking and State of Ohio, this 26th day of March, 1924.

DAVID DENELSBECK.
CLARENCE D. DILLE.
